US0D1067204S

(12) **United States Design Patent** (10) **Patent No.:** **US D1,067,204 S**
(45) **Date of Patent:** **** Mar. 18, 2025**

(54) **SUSCEPTOR**

(71) Applicant: **ASM IP Holding B.V.**, Almere (NL)

(72) Inventors: **Shujin Huang**, Tempe, AZ (US);
Junwei Su, Tempe, AZ (US); **Wentao Wang**, Chandler, AZ (US); **Xing Lin**, Chandler, AZ (US)

(73) Assignee: **ASM IP Holding B.V.**, Almere (NL)

(**) Term: **15 Years**

(21) Appl. No.: **29/840,695**

(22) Filed: **May 31, 2022**

(51) **LOC (15) Cl.** **13-03**

(52) **U.S. Cl.**

USPC **D13/182**

(57)

CLAIM

The ornamental design for a susceptor, as shown and described.

DESCRIPTION

FIG. 1 is a front perspective view of a susceptor, showing our new design;

FIG. 2 is a bottom perspective view thereof;

FIG. 3 is right side view thereof;

FIG. 4 is a left side view thereof;

FIG. 5 is front view thereof;

FIG. 6 is back view thereof;

FIG. 7 is a top view thereof; and,

FIG. 8 is a bottom view thereof.

1 Claim, 5 Drawing Sheets
